BEVERAGE DRINKING FOUNTAIN

John V. Pontrelli, 2650 Wallingford Road,
San Marino, Calif. 91108

Filed Oct. 5, 1967, Ser. No. 8,872

Term of patent 14 years

(Cl. D23—13)

The single figure is a perspective view taken straight on, showing the design of a beverage drinking fountain.

The side view of the beverage drinking fountain not shown is essentially the same in appearance as the side shown.

The dotted line showing is for illustrative purposes only.

I claim:

The ornamental design for a beverage drinking fountain, substantially as shown and described.
